UNITED STATES PATENT OFFICE.

JOHN W. YOUNG, OF FORT MORONI, ARIZONA TERRITORY.

SAFETY DEVICE FOR BRIDGES AND ELEVATED-RAILROAD STRUCTURES.

SPECIFICATION forming part of Letters Patent No. 282,024, dated July 24, 1883.

Application filed March 8, 1883. (No model.)

To all whom it may concern:

Be it known that I, JOHN W. YOUNG, a citizen of the United States, residing at Fort Moroni, in the county of Yavapai and Territory of 5 Arizona, have invented certain new and useful Improvements in Safety Devices for Bridges and Elevated-Railroad Structures; and I do hereby declare the following to be a full, clear, and exact description of the invention, such 10 as will enable others skilled in the art to which it appertains to make and use the same, reference being had to the accompanying drawings, and to letters or figures of reference marked thereon, which form a part of this 15 specification.

The object of this invention is to provide simple and effective means for preventing disasters in the event of the fall or destruction of railroad and other bridges or elevated-railroad 20 structures when trains or vehicles are passing over the same, there being brought into the service, when such an accident occurs, devices for supporting the cars or vehicles and holding them suspended until the passengers can be rescued and the cars or vehicles 25 removed to a place of safety.

The invention consists in stretching strong cables, chains, bars, or ropes along the track or roadway upon a bridge or elevated-railroad 30 structure and securing the ends of said cables, chains, bars, or ropes to abutments or anchors firmly fastened at the approaches of the bridge or elevated structure. These cables, chains, ropes, or bars are fastened to the 35 guard-rails between the track-rails, or to the wheel-guides upon a bridge or longitudinal timbers or girders of an elevated railroad structure; or they can be placed in any other position where they will not interfere with 40 the travel on the bridge and still be in position to uphold cars or vehicles in the event of the tearing away or precipitation of the bridge to the street, river, or ravine below. When 45 a bridge tears away from its piers or columns or is otherwise destroyed, the cables or their equivalents stretched above the roadway are not carried with the bridge, but remain in position to receive and hold the cars or vehicles, the axles of the latter dropping upon the cables, which catch and hold the cars or vehicles

in a state of suspension. Secondary cables at the sides of the track, secured in the same manner as the main cables, prevent the cars or vehicles from tipping off the lower cables.

Figure 1 is a perspective view, showing my 55 invention applied to a railroad-bridge spanning a ravine. Fig. 2 is a perspective view of a section of the bridge structure, showing safety-cables secured to the guard-rails and secondary cables arranged outside and above 60 the latter.

Two or more cables, chains, wire ropes, or bars, A, are stretched from anchors B or abutments firmly secured or embedded in the ground near or at the approaches to a railroad 65 or other bridge; or, in the case of an elevated-railroad structure, these cables or their equivalents can be secured to the columns or pillars located at the corners of intersecting streets, or at any intermediate points. The cables or 70 their equivalents extend from their points of anchorage across the bridge or along the elevated-railroad structure, and are held upon the guard-rails or beams C, running parallel 75 with the track-rails D, as is clearly shown in Fig. 1. In a bridge for ordinary vehicles the cables are attached to the customary wheel-guides or longitudinal timbers, or are stretched upon the roadway of the bridge, so as to be 80 inside or in proximity to the path taken by the vehicles. The fastening devices employed may be simple staples a, or equivalent devices, as generally it is not the intention to permanently 85 fasten the cables to the guard-rails or bridge structure, the fastening of the cables being merely resorted to to hold them in place and prevent their interfering with the travel on the bridge. In iron bridges these fastening devices a may be termed "guides" for the cables, because they are of such size as not to hug or 90 closely clasp the cables, thus not interfering with the longitudinal play or free expansion and contraction of the bridge structure. In certain instances I contemplate securing the bridge structure to the safety-cables by means 95 of fastening devices, which are of such construction and strength that the safety-cables will support or uphold the bridge structure when the latter tears away from its piers or support.

Secondary cables, chains, bars, or ropes E, two or more in number, located on or at a higher plane than the main cables, are arranged outside the track-rails or the roadway of the 5 bridge, and are supported upon suitable posts, G, which rise from the bridge structure or cross-beams of the bridge. These secondary cables, or their described equivalents, are also firmly anchored or otherwise secured at the 10 approaches to the bridge or between the different sections or stations of an elevated-railroad structure. Thus it will be manifest that both sets of cables, or their equivalents, are secured independently of the bridge structure, 15 and generally have no connection with the same, except through the weak or separable fastening devices or guide-staples, unless the bridge or other structure is intended to be upheld by the cables, when said fastening devices 20 are made strong enough to insure the firm and permanent connection of the cables with the bridge structure. In the event of the bridge or any section thereof giving way or being destroyed while a train or vehicle is passing over 25 the same, it follows that the lower or main cables, running between or in proximity to the track-rails and placed as near to the axles as possible, or running along or over the roadway of the bridge, will remain intact, or in position 30 to receive the car or cars or vehicle, the axles or body of the latter dropping upon said cables by reason of the precipitation or removal of the bridge structure. The distance the cars fall is comparatively short when the 35 cables are placed near to the axles thereof.

The secondary cables E, located on or at a higher plane and outside the track-rails or along the roadway occupied by vehicles passing over the bridge, afford lateral support to 40 the cars or vehicles and prevent them from tipping off from the lower or inner cables, as will readily be understood.

The above-described safety devices will lessen the liability of disasters and loss of life and 45 property, and add comparatively little to the expense of the bridge or structure upon which they are used.

It will be understood that in bridges having draw or movable sections the safety-cables are made in sections connected together by means 50 of strong and efficient clasp devices, which can be easily fastened and unfastened.

I am aware that it has been proposed to stretch wire ropes at the sides of a railroad-bridge and a single rope along the rail supports or ties, the object of the side ropes being to prevent cars from turning over in the bridge or striking the bridge structure, while the bottom rope prevents the lower part of the car from leaving the track or striking the bridge-frame. Ropes arranged in this manner are, 55 however, not designed or adapted for supporting cars or vehicles in the event of the precipitation of the bridge structure, because they have no independent anchorage, and are in fact 60 intimately secured to the supports which hold the ends of the bridge structure, so that in the event of the tearing away or destruction of said structure the various ropes will be carried 65 with it.

Having thus described my invention, what I claim as new, and desire to secure by Letters Patent, is—

1. The combination of two or more safety-cables or their equivalents with a railroad or 75 other bridge or elevated-railroad structure, said cables being anchored or secured at their ends independently of the bridge-span over which they pass, and arranged above the roadway between and in proximity to the track-rails, or in the path occupied by ordinary 80 vehicles, as and for the purpose herein set forth.

2. The combination of the cables A and E, having suitable end supports or anchors, B, with an ordinary railroad or other bridge se- 85 cured at its ends independently of said cables, as and for the purpose set forth.

In testimony whereof I affix my signature in presence of two witnesses.

JNO. W. YOUNG.
